INVENTOR.
Morris Earl

BY *M. C. Frank*
ATTORNEY

UNITED STATES PATENT OFFICE.

MORRIS EARL, OF OAKLAND, CALIFORNIA.

SOCKET JOINT FOR WIND MUSICAL INSTRUMENTS.

Application filed July 5, 1924. Serial No. 724,183.

To all whom it may concern:

Be it known that I, MORRIS EARL, a citizen of the United States, residing at Oakland, in the county of Alameda and State of California, have invented certain new and useful Improvements in Socket Joints for Wind Musical Instruments, of which the following is a specification.

My invention relates to improvements in wind musical instruments, and more particularly to the socket joint for such instruments.

Wind instruments of the character of the saxophone and clarinet type, have a mouthpipe disconnectible from the body of the instrument for cleaning and packing purposes chiefly, and the joint at the union of the said two elements as now manufactured, has deficiencies that render the instrument imperfect to a varying and surprising degree in producing clear and true tones, primarily because of more or less leakage of air at the joint.

As a repairer and reconditioner of reed instruments, I have found that such instruments as mentioned become defective in a very short time at the said socket joint, and an air leak at this joint affects every note on the instrument as it is at the head of the column of all the notes and consequently is of vital importance. The present joint consists of a cylindrical terminal socket in the body member and has a long kerf or slit thereto, and exterior thereto is secured a split ring or band equipped with a thumb-screw, for tightening the socket around and to the spigot end of the mouthpipe that slips within the socket. In practice this type of joint is far from ideal, as the leakage of air thereat together with a fit that permits more or less turning and lateral movement of the mouthpipe is very trying and annoying to the player of the instrument.

To make a perfect fit in the factory of each new instrument is a long and painstaking task, and of course would increase the price of the already high-priced article, and it is thought that the purchaser and user of the instrument will eventually wear a perfect fit at the joint. This desired attainment I have found not to be the case.

The major objects of my invention are to remedy the above-mentioned deficiencies by producing a rigid and air-proof socket joint without the aid of thumb-screws or the like, in a simple and inexpensive manner

that will be very durable and not necessitate periodic reconditioning.

I attain the above objects by the novel construction of my socket joint, and other objects and advantages of the invention will appear in the subjoined description of the accompanying sheet of drawings, in which:

Figure 1 is a view in side elevation of a mouthpipe connected to the upper portion of the body member of a reed instrument, my improved joint being shown in dotted lines. Fig. 2 is a view, on an enlarged scale and partly in section, of the joint constructed in accordance with my invention; and Fig. 3 is a similar view in section, but drawn to a smaller scale, of a modification of the male member of the joint.

Adverting to the drawing and figures 75 thereof: The numeral 4 denotes in general the mouthpipe of a saxophone, the latter being the instrument that I have selected to illustrate the embodiment of my invention, but the invention may be used on any 80 wind musical instrument where serviceable. 5 is the upper portion of the body member of the instrument, and 6 the customary keys thereof. 7 in Fig. 1 indicates in dotted lines the improved joint as a unit.

By reference to Figs. 2 and 3 I will now describe the joint in detail: 8 is the socket formed in the body member and has an out-flaring end 9. 10 is the spigot end of the mouthpipe 4, and has its free extremity 90 formed with a groove or recess 11, for the reception of a ring 12 of cork or other resilient suitable material. The ring may be secured in the recess by a thin coating of cement (not shown) or otherwise. The spigot 95 end is of a determined length as shown, and terminates in a tapered collar 13 in registry with the flare of the socket end 9. The said spigot end is smaller in diameter than that of the socket as shown at 14, to enable 100 it to be easily inserted in the socket, and the outside diameter of the resilient ring 12 is made larger than that of the socket interior diameter for sealing and bracing purposes, and which will be later described.

In the modification shown in Fig. 3, the collar 13' is a tapered ring slipped to position and secured to the mouthpipe as by soldering, or in any other approved manner. This collar forms an integral part of the 110 mouthpipe as does the collar 13. At present I employ the collar 13' to existing instru-

ments, and may also employ it in the manufacture of new instruments, or I may employ the collar 13 of Fig. 2.

In operation, the spigot end of the mouthpipe 4 is slowly forced into the socket 8, the resilient ring 12 compressing to position without tearing by reason of first engaging with the flaring end 9, and when the chosen position of the mouthpipe is determined with respect to the keys 6, the said mouthpipe is given a final light thrust for seating engagement, the two flaring surfaces meeting in rigid chosen engagement and braced by the reinforcing and sealing ring 12, thus the union of the two members is both proof against air leakage and lateral movement, and the joint may at any time be broken with ease and remade as often as necessary.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made, when desired, as fall within the scope of the appended claims.

Having thus described my invention, what I claim as new and desire to secure by Letters Patent of the United States, is the following:

1. A socket joint for wind musical instruments, comprising a body member provided with a socket having a flaring end of shallow depth and a mouthpipe having a spigot

end of formation adapted to enter said socket and contactingly seat on said flaring end, and said spigot end having near its extremity a narrow ring of resilient material to effect an air-seal thereat.

2. A socket joint for wind musical instruments, comprising a body member provided with a socket having a flaring end of shallow depth and a mouthpipe having a spigot end of formation adapted to enter said socket and contactingly seat on said flaring end, and said spigot end having near its extremity a recess of narrow width for the reception and securing therein of a resilient ring to effect an air-seal thereat.

3. A socket joint for wind musical instruments, comprising a member provided with a socket having a flaring end and a mouthpipe having a spigot end of smaller diameter than the socket for a determined length thereof; the said spigot end formed with a groove near its free end for the reception of a resilient ring and the opposite end thereof having a tapered collar adapted for registry in said flaring end for the seating of the mouthpipe in any chosen position in the socket, and the resilient ring adapted to form a reinforcement and air-seal for the joint.

4. In a mouthpipe for wind musical instruments provided with a spigot end, a recess formed near the extremity of said end for a sealing ring, and said spigot end further provided with a tapered collar spaced from said recess and parallel thereto for forming the other end of the spigot.

In testimony whereof I affix my signature.

MORRIS EARL.
